UNITED STATES PATENT OFFICE.

MAX SIMSON, OF NEW YORK, N. Y.

DESIGN FOR A JEWELRY SETTING.

Application filed November 27, 1925. Serial No. 15,559. Term of patent 7 years.

To all whom it may concern:

Be it known that I, MAX SIMSON, a citizen of the United States, residing in New York city, county and State of New York, have invented a new, original, and ornamental Design for Jewelry Setting, of which the following is a specification, reference being had to the accompanying drawings, forming part thereof.

Figure 2 is a view in perspective.

I claim:

The ornamental design for a jewelry setting as shown.

MAX SIMSON. [L.S.]
